FLUSHING OIL

Mathew L. Kalinowski and Morris Feller, Chicago,
Ill., assignors to Standard Oil Company, Chi-
cago, Ill., a corporation of Indiana

No Drawing. Application June 26, 1950,
Serial No. 170,468

11 Claims. (Cl. 252—170)

1

This invention relates to improved solvents of the type generally referred to as flushing oils and it pertains more particularly to an improved method and means for cleaning surfaces coated with so-called varnish deposits, sludge, etc., of the type which is formed for example in the crank cases of internal combustion engines.

During the operation of internal combustion engines (either spark ignition or compression ignition) with many types of lubricating oils, deposits are formed on surfaces, particularly in the crank case of the engines, which should be removed from time to time in order to avoid excessive wear, plugging of oil channels, etc. There are several kinds of deposits which accumulate on such surfaces, such as sludge deposits which may be removed by high boiling aromatic solvents, lacquer or varnish deposits which are much harder to remove, and carbon deposits which are usually bonded by the varnish deposits and when tend to flake off when the varnish deposits are removed. It is known that certain high boiling portions of the hydrocarbon product produced in the catalytic hydroforming of naphtha has beneficial properties for removing the sludge deposits (U. S. 2,410,613), but at ordinary temperatures it is relatively ineffective for removing the lacquer or varnish deposits. Such solvents have been combined with alkylated hydroformer polymer (U. S. 2,491,120) and phosphorous and sulfur-containing reaction products of olefin polymers of high molecular weight (U. S. 2,495,030), these latter compositions being beneficial from the standpoint of preventing engine scoring when employed as crank case flushing oils without unduly interfering with solvent properties. An object of our invention is to provide a flushing oil which has solvent properties superior to those obtainable in any prior art compositions and which are particularly effective in removing internal combustion engine varnish deposits.

While our improved solvent may be employed as a crank case flushing oil in engine crank cases or lubricating systems per se (with or without addition of a lubricating oil component for obtaining any desired viscosity) they are also valuable for cleaning engine parts in repair shops. Such shops may simply maintain a bath of such solvent at ordinary or elevated temperature and immerse in said bath for a period of a few minutes to several hours any metal parts which contain sludge, varnish or other deposits caused by oxidation, polymerization, etc. of oil on said surfaces.

2

We have discovered that the propane-insoluble fraction of crude fatty materials, which is obtained as a residue in amounts of the order of about .2 to 2 or more weight per cent when crude fats, fatty oils, or fatty acids split therefrom are subjected to propane fractionation, is remarkably effective as a solvent for engine varnish. The propane-insoluble residues from propane fractionation of crude fatty materials contain most of the color bodies which were present in the crude materials and are so dark in color that they are referred to in commerce as "ebony fats." The propane-insoluble residues from animal fats will be herein referred to as "ebony A" and from vegetable fatty oils as "ebony V." The properties of representative samples of ebony A and ebony V, respectively are approximately as follows (on a water-free basis):

	Property	Ebony A	Ebony V
20	Viscosity, Seconds Saybolt at 100° F.	6,500	930
	Viscosity, Seconds Saybolt at 130° F.	1,860	430
	Viscosity, Seconds Saybolt at 210° F.	300	100
	Ash, weight percent	1.3	.06
25	IA. P. I. Gravity, degrees	10	16
	Acidity ASTM (D-664 Mg. KOH/gm)	41	63
	Pentane Insoluble, weight percent	2.6	4.2
	Benzene Insoluble, weight percent	0.7	1.0
	Saponification Number	190	170
	Percent Fatty Acid	20	31
	Iodine Number	58	106

30 The above properties are, of course, merely illustrative and it should be understood that both the amount and properties of the ebony fats will depend on the nature of the crude fatty material which is subjected to propane fractionation and on the particular conditions employed for effecting the fractionation. The term "crude" means that color bodies and other materials insoluble in 6 to 30 volumes of propane at about 140 to 190° F. have not been removed, regardless of whether or not the material has been destearinated.

35 The method of fractionating fatty materials with propane is well known to those skilled in the art and is commonly referred to as the Solexol process currently in commercial use. A system for effecting such fractionation is described in considerable detail in U. S. 2,505,338. For most crude animal fats, vegetable oils and similar fatty materials (including fatty acids split from such fats and oils), the fractionation conditions are employed to give a propane-insoluble residue of approximately 1%, i. e. about .2 to 2% although in some cases such residue may be as 40 large as 5% or even 10%.

While ebony fats per se are remarkably effective as engine varnish solvents, their effectiveness may be enormously augmented by adding thereto a high boiling mixture of poly methyl aromatics, polycyclic aromatics and methyl and poly methyl polycyclic aromatics of the type generally referred to in U. S. 2,410,613 and more specifically defined in U. S. 2,491,120 and 2,495,030. While hydroformer "polymer" or bottoms is an excellent source of such high boiling aromatics, it should be understood, however, that these high boiling aromatics may be obtained as a neutral tar oil of similar boiling range and A. P. I. gravity obtainable from coal by-products. Another source of such high boiling aromatics is the catalytic cracking refractory stock as described in U. S. 2,335,596, although in the latter case the effectiveness of the high boiling aromatics may be improved by separating aliphatic components from the catalytic cracking refractory stock by extraction with known solvents such as furfural, dimethyl formamide, and the like. Properties of the mixture of poly methyl aromatics, polycyclic aromatics and methyl and poly methyl polycyclic aromatics are as follows:

Property	Range	Preferred Example
Boiling Range	350-650° F.	400-550° F.
A. P. I. Gravity	10-20°	16°
Flash (Tag Closed Cup)	Above 150° F.	Above 165° F.
Mixed Aniline Point	10-30° C.	20° C.
Kauri-Butanol	Above 100°	Above 150°
Viscosity, Seconds Saybolt at 100° F.	30-35	32
Percent Aliphatic Compounds	0-10	Less than 5

With respect to the boiling range, the end point should not exceed 650° F. and preferably should not exceed 625° F. in order that the solvent material may be free of condensed polycyclic aromatics of more than three rings and thus be safe from the point of view of possible carcinogenic properties. The solvent preferably has a 10% point of approximately 400° F. and a 90% point in the range of about 500 to 550° F.

The following test data will illustrate the remarkable effectiveness of ebony fats and particularly the combination of ebony fats with high boiling aromatics as hereinabove described. These tests were all made on materials coated with engine varnish by immersing the coated materials for a period of 15 minutes in a bath of the respective solvent or solvent mixture after which solvent was rinsed from the surfaces with a light naphtha. All of the test pieces had varnish coatings of substantially the same area and same type and quantity. The amount of varnish removal was determined visually.

Components	Ratio By Vol.	Flash Point, ° F., C. O. C.	Vis. SSU, 210° F.	Percent Removal of Engine Varnish	
				At 78° F.	At 160° F.
Ebony V		560	100	30	60
Ebony V+aromatics	9:1	275	69	70	75
Do	5:5	205	35	80	85
Do	1:9	200	29	30	30
Aromatics		165	-----	0	15
Ebony A		560	300	50	65
Ebony A+aromatics	9:1	365	-----	70	75
Do	5:5	215	37	90	90
Do	1:9	195	29	50	55
Aromatics		165	-----	0	15

From the above data, it will be seen that the high boiling aromatic mixture per se (as taught

in the prior art hereinabove referred to) is ineffective for removing engine varnish at 78° F. and is relatively ineffective for removing said engine varnish even at 160° F. (normal crank case operating temperatures). Even at the low temperature, the ebony compounds were two to three times as effective for removing engine varnish as was the high boiling aromatic mixture at the high temperature. Obviously, due to their similarity in composition, ebony A and ebony V could be mixed with each other in any desired proportion, but it will be noted that the ebony A is markedly superior to ebony V in its solvent properties for engine varnish.

Perhaps the most surprising result shown by the above data is the fact that the mixtures of the ebony fats with the high boiling aromatic mixtures produce results which are not cumulative or additive but which are highly synergistic.

For example, ebony V at 78° F. removes only 30% of the engine varnish. Adding 10 volume per cent of high boiling aromatics (per se ineffective at this temperature) raises the effectiveness of ebony V to 70%. Adding 50% of said aromatics raises the effectiveness of ebony V to 80%. Adding as little as 10% of ebony V to said aromatics gave 30% varnish removal. Similar synergistic effects are found in the ebony A-aromatics mixtures, the ebony A being somewhat more effective for engine varnish removal. For optimum varnish removal both the ebony fat and high boiling aromatic should be present in large proportions. By admixing the defined aromatic mixture with ebony fats, varnish removal can be effected at ordinary room temperatures and there is no longer any necessity of maintaining such a bath at 160° F. or of keeping the motor running during a flushing operation in order to maintain this high temperature level. However, use of our flushing oils in a running engine is advantageous since it insures circulation and intimate contact of the flushing oil with the parts to be cleaned.

The above data also show that the inclusion of as little as 10% of ebony fat to high boiling aromatics raises the flash point by as much as 30 to 35° F. The 50-50 mixture of ebony A with high boiling aromatics has a flash point of 215° F. Also, the viscosity of the substantially non-viscous aromatics is markedly raised by as little as 10% of ebony fat. Another attribute of the combination of ebony fat with the defined aromatic mixture is the effectiveness of the ebony fat in peptizing the sludge components so that they may be held in suspension in the aromatic mixture, thus markedly improving the latter with respect to its previously known functions.

Our mixtures of ebony fat and high boiling aromatics were also tested for cleaning varnish from varnish-coated engine pistons by dipping the pistons 5 to 15 times in a bath of the flushing oil composition maintained at a temperature of 140° F. with sufficient time between dips to permit drainage of excess flushing oil from the piston followed by a soaking period of about 15 minutes. Here again, the optimum solvent was one containing substantially equal parts by volume of ebony A and high boiling aromatics with mixtures preponderating in the ebony fat giving results superior to mixtures preponderating in aromatics. With the 50-50 mixture of ebony A and high boiling aromatics, it was noted that the varnish on the pistons had softened after the first dip. After the soaking period of 15 minutes followed by wiping off the flushing oil

with a cloth, the piston was cleaned of all varnish deposit. In a "varnish rating" test, wherein an average fouled piston has a rating of 5 and a completely clean piston has a rating of 10, the high boiling aromatics alone had no effect on the varnish rating after 5 dips at 140° F., while our 50-50 ebony A mixture improved the varnish rating from 5 to 7. After 15 dips the aromatics alone resulted in a varnish rating of only 5.5 while the 50-50 ebony A mixture produced a varnish rating of 8.5. A 15 minute soaking period at 140° F. followed by wiping or rinsing off the soaked surfaces is usually employed to effect removal of piston varnish.

It is the ebony fat and/or the ebony fat in combination with the defined aromatic solvent mixture which constitutes our improved solvent but it should be understood that our solvent may be diluted with a hydrocarbon oil for increasing or decreasing its viscosity particularly when it is employed in place of the usual lubricant for flushing out a lubricating system. Other known flushing oil additives may likewise be employed in addition to the essential component or components of our solvent. After a purging or solvent treatment of a varnish coated surface, it is usually desirable (but not always necessary) to rinse off residual solvent by means of a light hydrocarbon oil or other suitable rinsing liquid.

Having thus described our invention and preferred embodiments thereof, what we claim is:

1. The method of cleaning surfaces coated with internal combustion engine varnish deposits and sludge which method comprises washing said surfaces with a material produced as an approximately 1% to 2% propane-insoluble residue when a crude fatty material is extracted with propane.

2. The method of claim 1 wherein the crude fatty material is an animal fat.

3. The method of claim 1 wherein the crude fatty material is a vegetable oil.

4. The method of claim 1 wherein the crude fatty material is a crude fatty acid split from a crude fatty acid glyceride.

5. The method of claim 1 in which at least 2 volume per cent of the material is admixed with a fraction of aromatics boiling in the range of 350-650° F. and having an A. P. I. gravity in the range of 10° to 20°, said fraction containing substantial amounts of poly methyl benzenes, poly-

cyclic hydrocarbons and mono and poly methyl polycyclic aromatic hydrocarbons.

6. A flushing oil which comprises a mixture of aromatics boiling in the range of 350 to 650° F., said mixture having an A. P. I. gravity in the range of 10° to 20° and consisting chiefly of poly methyl benzene, polycyclic aromatics and mono methyl and poly methyl polycyclic aromatics in combination with at least about 2 volume per cent of a propane-insoluble residue of a crude fatty material, which residue constitutes only about .1 to 2% of said crude fatty material.

7. The flushing oil of claim 6 wherein the crude fatty material is an animal fat.

8. The flushing oil of claim 6 wherein the crude fatty material is a vegetable oil.

9. The flushing oil of claim 6 wherein the crude fatty material is a fatty acid split from a crude fatty acid glyceride.

10. A flushing oil which consists essentially of about 2% to 98% by volume of an aromatic solvent boiling in the range of 350° to 650° F., having an A. P. I. gravity in the range of 10° to 20°, and consisting chiefly of poly methyl benzene, polycyclic aromatics and mono methyl and poly methyl polycyclic aromatics in combination with about 98% to 2% by volume of an "ebony fat," which "ebony fat" is a propane-insoluble residue of a crude fatty material, which residue constitutes only about .1 to 2% of said crude fatty material.

11. A flushing oil which comprises about 50 to 90 volume percent of an aromatic solvent boiling in the range of 350° to 650° F., having an A. P. I. gravity in the range of 10° to 20°, and consisting chiefly of poly methyl benzene, polycyclic aromatics and mono methyl and poly methyl polycyclic aromatics in combination with about 10 to 50 volume percent of an "ebony fat" which "ebony fat" is a propane-insoluble residue of a crude fatty material, which residue constitutes only about .1 to 2% of said crude fatty material.
